UNITED STATES PATENT OFFICE.

FRANK J. DUTCHER, OF HOPEDALE, MASSACHUSETTS, AND CHARLES E. CHURCH, OF HARTFORD, CONNECTICUT, ASSIGNORS TO THE DUTCHER TEMPLE COMPANY, OF HOPEDALE, MASSACHUSETTS.

IMPROVEMENT IN MACHINES FOR ASSORTING TEMPLE-TEETH.

Specification forming part of Letters Patent No. 174,902, dated March 21, 1876; application filed January 21, 1876.

To all whom it may concern:

Be it known that we, FRANK J. DUTCHER, of Hopedale, in the county of Worcester and State of Massachusetts, and CHARLES E. CHURCH, of the city and county of Hartford, in the State of Connecticut, have invented an Improved Mechanism for Assorting Temple-Teeth, &c., of which the following is a specification:

This invention is specially adapted to assort loom-temple teeth or pins, but it may be applied to assort nails, screws, or pegs, for various other uses, but unprovided with flanged or enlarged heads, and to place such teeth or nails in such position that all the points project in the same direction.

The invention consists in a movable celled carrier, provided with cells corresponding with the entire shape of the teeth to be selected and assorted, in combination with a brush or clearer to remove from the cells of the carrier any teeth lodged therein that fail to correspond in the position of their points with the point-receiving portion of the cell; also, in a celled carrier combined with a receiver to receive the teeth or nails from the cells of the carrier; and in other features of invention hereinafter set forth.

Figure 1 represents a side view of the assorting mechanism; Fig. 2, a view of the opposite side of the machine, with the side of the hopper removed; Fig. 3, an inner side view of the hub or rest by which the carrier is sustained and over which it moves, and of the ejector to remove a tooth from a cell; Fig. 4, an edge view of the carrier; Fig. 5, a side and edge view of the receiver; Fig. 6, an end view thereof; Fig. 7, a view of the follower arranged in the receiver; Fig. 8, a modified form of carrier; Fig. 9, a temple-tooth enlarged; Fig. 10, a tube filled with teeth, as hereinafter described.

The frame *a* of the machine is of any suitable shape, and sustains the driving-shaft *b*, provided with two pulleys or wheels, *c*, (one only being shown, the other being of same size and directly behind the one shown in Fig. 1,) and with a cam, *d*, and an eccentric, *e*, the shaft in this instance being rotated by a

crank-handle, *f*, but instead of the handle a pulley may be used. One pulley, *c*, is connected by a band, *g*, or otherwise, with a pulley or wheel, *h*, on a shaft, *i*, having connected with it a stirrer or agitator, *j*, the latter placed in a hopper, *k*, in which are placed the teeth or nails to be assorted, so as to turn in the direction of the arrow thereon, and crowd the teeth up against the carrier *p*, and a second pulley or wheel (not shown) is connected, by a crossed band, *l*, or otherwise, with a wheel or pulley, *m*, on a shaft, *n*, provided with a brush, or equivalent, *o*, also shown as arranged in the hopper and adapted to move in the direction of the arrow, so as to remove from the cells *q* in the carrier any teeth that may lodge improperly in the cells.

The guide *r*, for the carrier *p*, is shown in Figs. 3 and 4 as a stationary annular plate, provided with a curved rim, *s*, and an annular flange, *t*, the latter fitting within the cylindrical end of the carrier, forming a bottom to the cells *q*, except at the point *u*, where the flange is omitted, in order to permit the ejector *v*, composed in this instance of a finger provided with two prongs adapted to enter the cell from the under side, the fingers being carried by a slide, *w*, adapted to be raised by a cam, *d*, on shaft *b*, and to be depressed by a spring, *y*, bearing on the pin *x*, or in any other suitable or known way, the particular devices for moving the ejector not being essential, as the form of such may be readily varied in many ways.

The carrier is shown as provided with a ratchet-hub, *a'*, and beside it on shaft *b* is a cam, *e*, arranged to strike and move a pawl-carrying arm, *b'*, provided with a pawl, *c'*, adapted to engage the ratchet and move the carrier intermittently, the ejector operating during the time that the carrier is at rest.

The devices for imparting an intermittent motion to the carrier may be variously modified, and for the devices shown we may use any suitable or known devices to impart an intermittent motion from a continuously-moving shaft.

The carrier is provided with cells *q*, of a form corresponding with one-half the tooth

or nail to be picked up by it, supposing the tooth or nail cut in the direction of its length.

The carrier will be of a thickness substantially equal to the diameter of the teeth to be operated on, and at the pointed or tapering end of the cell we fill in the bottom, forming an inclined support for the pointed end of the tooth, and a tooth correctly placed in the carrier will present its upper side substantially flush with the top of the carrier, and in every instance the cell, to operate correctly, must be made to conform to, and to receive, as above described, the article to be selected.

For temple-teeth, the cells are of the configuration shown, for temple-teeth are cylindrical pins pointed at one end only. As the carrier *p* moves in the direction of the arrow thereon, (see Fig. 2,) the temple teeth or pins fall in or are lodged in the cells *q*, the agitator keeping the mass of teeth heaped up against the periphery of the carrier. If a tooth or pin lodges in the cell, with its point in the direction of the point *d'* of the cell, then such tooth or pin will pass with the carrier from the hopper and over the ejector, but if a tooth or pin rests in the cell with its unpointed end at the point end of the cell, then the brush or clearer *o* will remove from the cell the tooth or pin not fitted correctly into the cell. A temple tooth or pin, *e'*, correctly placed in a cell and removed from the hopper, will be brought over the ejector, as shown in Fig. 3, said figure showing the carrier removed, and with the tooth placed directly over the ejector, the ejector is raised carrying with it the tooth or pin, placing it in the receiver *f'*, provided with a channel, *g'*. (See Figs. 5 and 6.) At the lower end of this channel is placed a pivoted catch, *h'*, held pressed into the channel and across it by a spring, *i'*, and as the tooth is pressed by the ejector into the channel the catch yields, allows the tooth to pass it, and then moves forward under the tooth and enters between the prongs of the ejector, and serves to sustain the tooth when the ejector is withdrawn. A follower, *j'*, in this channel bears on the uppermost pin in the receiver, and rises as the receiver is filled. This receiver is held to the frame *a*, in this instance, by a clamp, *k'*, controlled by a set screw to permit the receiver when filled to be removed from the machine and placed in another machine in which the pins, teeth, or nails, so arranged with points all in one direction, may be driven from the receiver into the article to be made.

If loom-temples are to be made, the receiver filled with temple-teeth will be removed to a machine adapted to set the teeth in the usual roller, and the receiver will be placed in such position that the points of the teeth will be uppermost, (see Fig. 6,) and instead of the catch a rotating separating device adapted to fit about one tooth, or a device adapted to separate one tooth from the row, may be used to remove the teeth, one by one, from the receiver, and as each tooth issues

from the receiver it may be caught between fingers or equivalents that will hold and present the tooth in the proper position to be driven by suitable mechanism into a roller. The follower will be pressed forward against the pins to keep them from upsetting.

It is obvious that the shape of the carrier may be changed, and we may use a disk, as in Fig. 8, wherein the cells *q* are in a flat annular disk, and, in connection with such disk, a support for the teeth or pins will be employed under the cells, except at the point where the teeth are to be discharged. This disk will preferably be placed at an angle to the horizon, and will have an intermittent motion imparted to it, as described, with reference to the other carrier, and a clearer or brush will operate to remove teeth not properly within the cells.

Instead of employing the agitator, the hopper might be arranged with an inclined bottom, so as to direct the mass of teeth upon the wheel just in advance of the clearer *o*.

So far the only way described for discharging the teeth from the carrier has been by the ejector, but it is obvious that the receiver may be placed at the under side of the cell, and when a cell comes opposite an opening, as at *u*, in the bottom-forming rim for the cells, the pins or teeth being unsupported at their unpointed ends will drop through the cells butts first, the cells being large enough for this purpose. The teeth cannot possibly fall point first, because the pointed end is supported by the carrier after the supporting surface or rim sustaining the butts is removed. This arrangement would deliver the teeth in a tube or receiver with the butts all in one direction, as in Fig. 10, from which tube the teeth may be delivered one by one to a pair of fingers or holders, and then to the driving or setting mechanism.

We are not aware that a mechanism has ever before been devised to automatically select and present, with points all in one direction, teeth, nails, pins, screws, or pegs, unprovided with enlarged heads or flanged heads, and such being the case we do not desire or intend to limit this invention to the particular devices shown for performing the several novel and useful steps, as described, but intend by our claim to cover any equivalent mechanisms adapted, through cells in a carrier or plate, to select the teeth or other articles to be arranged, with points in one and the same direction.

The follower is held in the receiver *f'* by means of the plate *m'*, and is provided with a friction-spring to hold it in position when not moved positively. A pin, *n'*, and spring hold the arm *b'* against the cam.

In Fig. 10 we show an escapement, *r'*, and a rod, *t'*, to move it, and the movement of the escapement permits the teeth to pass out of the tube *a'*, one at each vibration of the escapement, and a movable rest, *u'*, will receive the butt of the tooth and sustain it until

caught by a nipper to remove it to the position where it is to be driven. The upper end of the tube or receiver α' , (see Fig. 10,) adapted to receive the teeth allowed to fall therein, is inclined as shown at w' , the inclined portion sloping upward in the direction of the rotation of the carrier, the arrow 2 showing this direction; and this inclination is necessary, because the tooth falls as the carrier moves, and the inclined surface gives the tooth time enough to fall or be received on the inclined surface, and the tooth then slides down such surface into the tube. In some cases we may provide the lower end of the tube or receiver α' with a transverse opening at its foot, and we will use a horizontally-reciprocating ejector to drive the teeth from the tube into a receiver suitably constructed to receive and retain the teeth parallel each with the other.

We claim—

1. A carrier provided with cells shaped to conform to the entire outline ends included of the tooth, pin, or nail to be operated on, and adapted to receive teeth, pins, or nails from a mass of teeth, pins, or nails, and remove them from the mass to assort them, in combination with a clearer to remove from the cells, teeth or pins lodged therein with the points or butts in opposition to the point or butt-receiving portions of the cells, all substantially as described.

2. A celled carrier provided with cells shaped to correspond with and to receive the entire sides and ends of the teeth or nails, in combination with a clearer to remove teeth improperly lodged in the cells, and with an ejector to remove the teeth or nails from the cells, substantially as described.

3. A movable celled carrier provided with cells conformed in shape to the sides of the teeth or nails to be selected, in combination with a support under the cells of the carrier, to support the nails except at the point at which they are to be discharged.

4. A movable carrier provided with cells to receive teeth or nails, as described, a support placed under the cells, and adapted to sustain such teeth or nails except at the point where they are to be discharged, in combination with a receiver to receive the teeth or nails, with points directed in the same direction.

5. A movable celled carrier, substantially as described, a support, and an ejector, in combination with a receiver, to receive the teeth or pins with points arranged in the same direction.

6. A receiver and catch, in combination with an ejector provided with a forked end, substantially as described.

7. The combination of a receiver for the teeth or nails and a catch to retain the last tooth inserted in the receiver, with a follower to keep the first tooth in the receiver in a position parallel with the last tooth, substantially as described.

8. A celled carrier and a clearer, in combination with an ejector and a receiver, combined and adapted to operate substantially as described.

In testimony whereof we have signed our names to this specification in the presence of two subscribing witnesses.
